ATTORNEY

UNITED STATES PATENT OFFICE.

JOEL JENKINS, OF MONTCLAIR, NEW JERSEY.

SAFETY-PIN.

SPECIFICATION forming part of Letters Patent No. 276,971, dated May 1, 1883.

Application filed January 2, 1883. (No model.)

To all whom it may concern:

Be it known that I, JOEL JENKINS, of Montclair, Essex county, State of New Jersey, have invented a new and useful Improvement in Safety-Pins; and I do hereby declare the following to be a full, clear, and exact description of the same, reference being had to the accompanying sheet of drawings, forming part of this specification.

10 This invention is in the nature of an improvement in safety-pins; and the invention consists in a safety-pin shield having invisible seams and struck up from a blank of the shape hereinafter described; and the invention also consists in a safety-pin with the face of its shield countersunk below the wire of the pin, as stated herein.

15 In the accompanying sheet of drawings, Figure 1 represents a plan view of the blank. Fig. 2 is a front elevation of shield completed. Fig. 3 is a back elevation of shield completed. Fig. 4 is a view of shield on pin. Fig. 5 is a cross-section taken in line $x x$, Fig. 4. Fig. 6 is a front elevation of completed pin and shield.

20 Similar letters of reference indicate like parts in the several figures.

25 As is well known, the shields for safety-pins have heretofore been made from blanks of many different shapes, so that when the blank 30 has been folded in a given way the shields for the safety-pins have been completed; but in all such shields the joints produced by folding together the several parts of the blanks left seams that were not only unsightly, but 35 frequently produced an irritating surface that would scratch, so that the pins with such shields did not present a finished appearance, and were not strictly harmless.

40 The purpose of this invention is to make a shield for safety-pins that can be so struck or drawn up as to render the necessary joints or 45 seams in the shield practically invisible. To that end in the construction of my shield I stamp out with suitable dies a blank, A, with a projection, a , in the center of its upper edge, gradual curved lines b forming its upper edge, rounded corners c , beveled sides d , and slightly-curved lower edge or base, e , the whole outline resembling somewhat that of a 50 crown. The blank, having the foregoing shape of any desired size, is then by suitable dies of the requisite proportion and form struck or

drawn up until the projection a , and curved edge b , rounded corners c , and beveled sides d assume the form of a completed shield, B, 55 shown in Figs. 2 and 3. Now, when the several parts of the blank A are in this way drawn up to form a completed shield, the points of juncture or places at which the several edges of the blank meet, as at f and g , are practically invisible, so that the shield, to all intents and purposes and in appearance, is as if it were made by casting it in a mold, instead of simply drawing it up from sheet-metal by means of dies. Therefore no unsightly seams 60 are apparent to mar the finish of the shield, and none oppose their rough and jagged edges to irritate and wound the skin of the wearer. The completed shield in this way made is secured to the wire of the pin by creasing the 65 shield about or around such wire, as at h . Safety-pins have had their shields fixed to the pins in a similar manner heretofore—*i. e.*, creasing; but in creasing my shield to the pin I so 70 increase the surface of the shield as to bring the creasing entirely around the end of the wire of the pin and up both sides of the face of the shield, the crease being so deep that the face k of the shield will have its surface countersunk below the surrounding wire of the pin 75 as if it were inclosed in a frame. (See Fig. 5.) This not only adds to the general appearance of the pin, but it permits nothing to come in contact with the body of the wearer excepting the smooth rounded outline of the wire at the 80 end of the pin covered by the metal of the shield.

Having now described my invention, what I claim as new, and desire to secure by Letters Patent, is—

1. A safety-pin with its shield made from a blank of the form or pattern shown, and for the purpose hereinbefore described.

2. In a safety-pin, the shield B thereof constructed with invisible seams or joints, as and for the purpose described.

3. In a safety-pin, the face of the shield thereof countersunk below the surface of the wire of the pin, which is inclosed by the shield, as and for the purpose described.

JOEL JENKINS.
